BED END HOLDER

Filed April 4, 1928

R. A. Thomas

A. J. Birchler INVENTOR

BY Victor J. Evans

WITNESS:

ATTORNEY

UNITED STATES PATENT OFFICE.

ALBERT J. BIRCHLER, OF SPRINGFIELD, MISSOURI.

BED-END HOLDER.

Application filed April 4, 1928. Serial No. 267,310.

This invention relates to a holder for various articles, such as the ends of beds, for supporting such articles while the same are being painted or otherwise treated and the 5 device can also be used to hold articles in show windows and the like.

This invention also consists in certain other features of construction and in the combination and arrangement of the several 10 parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is an elevation of the device, showing it in use as supporting an end of a bed.

Figure 2 is a front view showing the sliding clamp on the upright.

Figure 3 is a section on line 3—3 of Figure 1.

In these views, the numeral 1 indicates a base which is supported at each end by a caster wheel 2. An upright 3 is carried by the base and this upright is formed with a longitudinally extending slot 4. A split clamping member 5 is slidably mounted on the upright, with its ends bent at rightangles and extending parallel to each other with the ends connected together by the bolts 6 so that by tightening the thumb nuts on these bolts, the clamp 5 will be held in adjusted position on the upright. The end 7 is of considerable length and each end is formed with a centrally arranged opening 8. The extremity of each part of the end 7—it being understood that this end is formed in 20 two parts by the opening 8—is split to form the tongues 9 and 10, the tongue 9 being bent over at rightangles while the tongue 10 is straight. One tongue 9 is bent in one direction and the other tongue 9 is bent in an opposite direction, as clearly shown in Figure 2.

The tongues 10 are adapted to enter the opening in the bedpost A which receives a part on the side of the bed, while the tongues 9 engage one side of the post. A bolt 11

passes through the clamp 5 and through the opening 8 in the end 7 and has a hooked end 12 for engaging one of the pins 13 in the bedpost, the outer end of the bolt having a thumb nut 14 thereon so that when the nut is tightened, the hooked end, engaging the pin, will 55 press the post against the tongues 9 with the tongues 10 engaging the opening in the post.

The base is provided with a pin 15 which is adapted to receive the hole in the lower end of the post which is designed to receive the 60 caster wheel of the post.

Thus I have provided simple means for holding an end of a bed in upright position so that it may be painted and by using two of these devices, one at each end of the bed end, 65 the said end can be easily transported from place to place or held in upright position in a show window or the like for display purposes. By making the clamp 5 adjustable on the upright, the device can be used with 70 different sizes of bedposts.

It is thought from the foregoing description that the advantages and novel features of my invention will be readily apparent.

It is to be understood that I may make 75 changes in the construction and in the combination and arrangement of the several parts, provided that such changes fall within the scope of the appended claim.

What I claim is:—

A device of the class described comprising a base, an upright on the base having a longitudinally extending slot therein, a clamp slidably mounted on the upright, means for holding the clamp in adjusted position, one end of 85 the clamp being extended and formed with tongues some of which are straight and others of which have their ends bent at rightangles, the straight tongues entering a slot in the article to be supported and the bent tongues engaging flat portions of the article, a bolt carried by the clamp and passing through the slot in the upright and having a hook-shaped end for engaging part of the article to be supported and caster wheels carried by the base. 90

In testimony whereof I affix my signature.

ALBERT J. BIRCHLER.
